[57] CLAIM

The ornamental design for a utility box for pickup trucks, as shown and described.

DESCRIPTION

FIG. 1 is a perspective view of a utility box for pickup trucks showing our new design;

FIG. 2 is a front elevational view, the rear being a mirror image thereof;

FIG. 3 is a top plan view thereof;

FIG. 4 is a bottom plan view thereof; and

FIG. 5 is an end elevational view, the opposite end being a mirror image thereof.

FIG. 1.

FIG. 2.

FIG. 3.

FIG. 4.

FIG. 5.
